Patented April 26, 1881.

UNITED STATES PATENT OFFICE.

WILLIAM E. BUDD, OF CHATHAM, ASSIGNOR OF ONE-HALF TO JAMES BRYCE, OF MADISON, NEW JERSEY.

BREECH-LOADING FIRE-ARM.

SPECIFICATION forming part of Letters Patent No. 240,653, dated April 26, 1881.

Application filed October 1, 1880. (No model.)

To all whom it may concern:

Be it known that I, WILLIAM E. BUDD, of Chatham, in the county of Morris and State of New Jersey, have invented certain new and useful Improvements in Fire-Arms, of which the following is a specification.

Although my invention is applicable to breech-loading rifles and shot-guns of various kinds, it is especially intended for use in what are known as "hammerless" shot-guns, in which the hammers work under cover of and are concealed by the breech-block.

My invention consists in the combination, in a breech-loading fire-arm, of a barrel and a base plate or piece, lugs upon one part engaging with recesses in the other part, a longitudinal rod inserted through said lugs and the part receiving said lugs, for securing said barrel to said base plate or piece, and a breech-block, through which said rod passes, and which is movable upon said rod.

It also consists in the combination, with said base plate or piece, said barrel, and said longitudinal rod, of a novel arrangement of spring-catch for holding said rod in place.

It also consists in certain novel means whereby the breech-block is locked to the above-described longitudinal rod, and also to the barrel.

It also consists in a novel means of adjusting or regulating the pull of the trigger of a fire-arm.

It also consists in certain novel features in the construction of the shell-extractors, and in a novel manner of securing them in the breech-block by means of pins, which serve as indicators to show whether either or both barrels have been fired.

It also consists in various other details of construction, to be hereinafter described.

Though my invention is here shown as embodied in a double gun, certain features thereof are equally applicable to single guns.

In the accompanying drawings, Figure 1 represents a longitudinal section between the barrels of a double shot-gun embodying my invention, certain parts being broken away to reduce the length, and the breech-block being shown as closed. Fig. 2 represents a view similar to Fig. 1, except that the breech-block is shown as drawn back for the purpose of

loading. Fig. 3 represents a side view of the base plate or piece, which forms an important feature of my gun. Fig. 4 represents a transverse section upon the line $x x$, Fig. 3. Fig. 5 represents a plan of the gun, a portion of the breech-block being broken away the better to illustrate my invention. Fig. 6 represents a longitudinal section through one of the barrels, the gun being shown as loaded and cocked. Fig. 7 represents a similar view after the hammer has been let down. Fig. 8 represents a transverse section upon the dotted line $y y$, Fig. 5. Fig. 9 represents a similar section upon the dotted line $z z$, Fig. 5. Fig. 10 represents a similar section upon the dotted line 65 11, Fig. 5; and Fig. 11 represents a perspective view of one of the extractors and indicator-pins detached from other parts.

Similar letters of reference designate corresponding parts in all the figures.

A designates the barrels, which may be made in any ordinary manner and of suitable shape, and the bores $a a$ of which are suitably chambered at the breech to provide for the reception of the shell-extractors.

B designates a base plate or piece of cast metal, such as malleable cast-iron or cast-steel, to which all the parts of the gun are attached. The base plate or piece B has an approximately plain upper surface, as shown clearly in Fig. 3, 80 and the barrels are faced off upon the under side and have a long bearing upon said base plate or piece. One of said parts—in this example of my invention the base-plate B—is constructed with lugs b , projecting upward 85 from its upper surface, and the other of these parts—in this example of my invention the barrel A—is constructed with recesses c , which correspond to said lugs and receive them.

C designates a round rod or locking-bolt, inserted longitudinally through a hole in the lugs b and through the barrels, thus locking the barrels securely to the base plate or piece, and at the same time affording provision for their convenient detachment from each other, 95 when desirable.

In order to prevent the round rod C from being accidentally displaced, I employ a spring, d , which engages with a notch, d' , in said rod and prevents the withdrawal of the latter until 100

the spring may be deflected to draw it out of the said notch. The notch with which the said spring engages is in one side only of the rod, and hence all that is necessary to disengage 5 said rod from said spring is to turn the rod partly round, disengaging the notch d' from said spring d , and then draw the rod out.

In addition to the rod or locking-pin C , I have here represented a device for preventing 10 the detachment of the barrel from the base-plate B , consisting of a short shaft or spindle, a' , inserted through a hole in the base-plate B , and provided at one side of its upper end with a laterally-projecting lip or fin, which, by the 15 turning of the said shaft or spindle, is made to engage with a cut or groove in the breech of the barrel.

Upon the lower end of the shaft or spindle a' is a crank or arm, b' , by means of which it 20 may be turned partly round to lock or unlock the barrel from the base-plate. Though both the rod C and the shaft or spindle a' are here represented, one only may be sufficient.

The ends of the projecting lugs b and the 25 ends of the grooves or recesses c may be inclined toward the breech, as clearly shown. When so constructed it is obvious that the barrel cannot be removed from the base-plate B without moving it also slightly in a longitudinal direction. When, however, the shaft 30 or spindle a' is turned so as to cause the lip or fin upon its upper end to engage with the groove or cut in the breech of the barrel, such longitudinal movement of the barrel upon the base-plate is prevented, and hence the barrel 35 cannot be detached from the base-plate.

In order to hold the wood forearm of the stock firmly upon the base plate or piece B , I provide the under side of the latter with pins 40 or teats c' , (see Figs. 3 and 4), which enter the wood of said forearm, and enable the screws usually inserted through the base-piece into the wood to be dispensed with.

D designates the breech-block, which is composed of a steel or iron casting having in it 45 two cavities, e , side by side, for the reception of the hammers, as hereinafter more fully described. As clearly represented in Figs. 9 and 10, the breech-block D is constructed with a 50 dovetailed rib or longitudinal projection, e' , which engages with a correspondingly dovetailed groove or slideway in the upper surface of the base plate or piece B , thus providing for the proper guidance of the breech-block in its 55 movement toward and away from the breech of the barrel. In order to still further aid in guiding said breech-block, I preferably extend the rod or locking-pin C through the same, it being provided with a hole for the reception 60 of said rod, as shown clearly in Figs. 1 and 2. Considerable strain upon the base plate or piece would be produced by the recoil of the charge upon the breech-block, and to insure the said base-plate against springing or breaking, I provide it with downwardly-projecting 65 lugs or ears a^3 at the breech of the barrel,

whereby its strength is greatly increased, as shown in Fig. 3.

I will now describe the means whereby the breech-block D may be moved back and forth 70 as desired, premising, however, that other suitable means might be used without departing from my invention.

E designates a lever, of peculiar form, pivoted to the breech-block D at e^2 , and hollowed 75 out upon the under side, so as to receive between its walls a link, F , which is pivoted in the base plate or piece B to a pin, f , forming a fixed fulcrum, and which is connected with said lever by a pin, f' , passing through a slot 80 in the end of said link. The hole in the opposite end of the link F , through which passes the pin f , is also slightly elongated, so that the link may have a slight longitudinal movement as the lever is swung back and forth to open 85 and close the breech. The slot through which the pin f passes provides for making a sliding connection between the link and its fulcrum, so that when the pin f' , which unites the link with the lever, moves below a direct line from 90 the pin f to the pin e^2 , the link slides forward upon its fulcrum-pin f and prevents any tendency to pull back the breech-block. As shown clearly in Fig. 1, the pin f' , when the lever E is closed entirely down, as there shown in full 95 outline, passes below a straight line drawn from the pin f to the pin e^2 , and hence a backward force—such as that produced by the recoil of the breech-block—would have no tendency whatever to raise the lever E and draw back 100 the breech-block.

In order to hold the breech-block against recoil, the link F is constructed with a shoulder, a^4 , against which the end of the lever E bears when the breech-block is moved inward, 105 as shown clearly in Fig. 1. In order, however, to still further guard against the backward movement of the breech-block, I employ a lever, G , pivoted at f^2 to the breech-block, and adapted to engage with a catch in the barrel. 110 The lever G has at its forward end an eye, f^3 , which is adapted to engage with a pin, f^4 , projecting from the top of the barrel, when the breech-block is pushed up tightly against the breech of the barrel. Attached to the lever 115 G , between its fulcrum f^2 and the eye f^3 , is a bolt, g , which, by a spring, g' , is constantly pressed downward into a notch, g^2 , in the rod C , thus locking the breech-block to the rod C and transmitting, in a direct line, the strain 120 produced by the recoil of the breech-block. To still further hold the breech-block against 125 backward movement, the lever E is provided at its end with a notch, h , and when said lever is closed down into the position shown in full outline in Fig. 1 the notch h engages with the end of the rod C in a manner clearly shown in Fig. 1, and still further serves to hold the breech-block in place. The breech-block being thus held closed or locked to close the breech, 130 it is necessary, in order to draw back the breech-block, that the notch h be disengaged

from the rod C, that the bolt *g* be moved or raised out of engagement with the notch in the rod C, and that the eye *f*³ of the lever G be raised from the pin *f*⁴ upon the barrel. The 5 first movement of the lever E from the position in full outline in Fig. 1 to that shown in dotted outline disengages the notch *h* from the rod C, and by means of a shoulder, *i*, upon said lever the tail of the lever G is depressed 10 and the bolt *g* raised sufficiently to disengage it from the notch in the rod C, while the end of the lever G in which is the eye *f*³ is raised sufficiently to disengage said eye from the pin *f*⁴, thus leaving the breech-block free to be 15 moved back. The movement of the lever E is continued until the breech-block is drawn back to the full extent of its movement, when the lever E and link F will have assumed the positions shown in full outline in Fig. 2. 20 It will be observed that the rear portion of the base plate or piece B is constructed with a cavity, *B*', in its upper side, and the link F and lever E are of such shape that when closed down, as seen in Fig. 1, these parts will be 25 under cover of the cavity *B*' and partly concealed from view.

I will now describe the construction of the shell-extractors and the method of attaching them to the breech-block, and also the peculiarities of the lock mechanism.

The breech-block D is constructed with two cylindric cavities, *j*, which are side by side, one in line with each bore *a* of the barrel, and H designates the extractors, each consisting 35 of a ring-shaped or annular sleeve fitting inside one of the cavities *j* in the breech-block D, and a projecting curved finger or extension, *k*, having an upturned lip, *l*, upon the end thereof, which is adapted to project over the 40 edge of a spent shell and withdraw the latter when the breech-block itself is drawn back for the purpose of loading. I I designate metal plugs, which are inserted within the ring-shaped portions of the extractors, and 45 which are screwed in holes in the bottoms of the cavities *j* of the breech-block, and which are fitted somewhat loosely to the extractors, so that the extractors may, when desirable, be withdrawn from between the said plugs and 50 the sides of the cavities *j*. Through the plugs I are inserted the firing-pins *m*, which are prevented from slipping out from the plugs by a simple device, hereinafter explained.

Turning, now, to the lock mechanism, K K 55 designate hammers, which are pivoted at *n*, and which are provided with short arms acted upon by the ordinary mainsprings, K'.

L designates one of the triggers, pivoted at *o*, and having a notch, *p*, with which a projection, *q*, on the hammer engages. When the hammer is cocked the trigger is pressed forward to engage with the hammer by a leaf-spring, *r*. As shown clearly in Figs. 6 and 7, the spring *r* is held by a screw, *r'*, which forms 65 a support therefor, and which may be inserted in either of three holes there shown, to cause

the spring to press with greater or less force on the trigger and adjust the pull thereof. It is very desirable that some provision be made for locking the trigger when the hammer is 70 cocked, so that it cannot be pulled off, and to provide for this I form in the trigger a notch, *s*, and pivot to the under side of the trigger-plate M a locking-plate, *s*², which may be turned to engage with said notch to lock the 75 trigger, or turned in the opposite direction to free it. This locking-plate being directly back of the trigger, it may be easily turned to free the trigger just before the latter is pressed by the finger.

As clearly shown in Fig. 10, the hammers K and triggers L are arranged at an angle to each other—that is, they converge toward the finger-pieces of the triggers—so as to bring the latter near together and well under the 85 trigger-guard N, which is secured to the trigger-plate M, in the usual way.

As before stated, the breech-block D has in it two cavities, *e*, for the reception of the hammers, and when the breech-block is moved 90 back the shoulders *t* thereon bear upon the plain faces of the hammers K and cock them.

It will be seen by reference to Fig. 7 that when the face of the hammer K bears upon the firing-pin *m* it is also against the shoulder *t*, and as soon as the backward movement of the breech-block commences the said shoulders carry the hammers away from the firing-pins, and hence it would be impossible for the hammers to strike the firing-pins and explode the shell unless the breech-block is at its farthest position inward—that is, tightly against the breech.

As seen most clearly in Figs. 1 and 2, the stock O is held securely between the rear portion of the base plate or piece B and the trigger-plate M by the screws *u*; and it will be observed that the gun is complete with all its working parts concealed, and may be fired even before the wooden stock is secured.

I will now describe the means whereby the extractors H are held in place in the breech-block, and the manner in which the said means is applied so as to form indicators to show whether the charges have either or both of 115 them been fired. This feature is shown most clearly in Figs. 6, 7, and 9.

As before said, each extractor comprises a ring-shaped or annular sleeve fitting in a cylindric cavity or socket, *j*, in the breech-block, 120 and the extractors are secured therein by means of pins *v*, which are inserted transversely through the breech-block and the ring-shaped or annular portions of the extractors. These pins *v* are of novel construction, to permit the withdrawal of the extractors from the breech-block, or, rather, to permit the breech-block to be drawn away from the extractors, leaving them in the ends of the bores *a* of the barrel when the gun is loaded. This construction and arrangement of extractors provides for drawing back with the breech-block 130

either extractor for loading, leaving the other extractor in the barrel. The ring-shaped portions of the extractors H are provided in opposite sides with holes w, for the reception of the pins v, and with slots w', extending from the said holes rearward to the end of the extractor, as shown in Fig. 11, and of less width than the said holes. The pins v comprise portions v', of lesser diameter than the other portions thereof, and when raised, as shown in Figs. 6 and 9, the said portions of lesser diameter come opposite the narrow slots w' in the annular portion of the extractor H, and permit the ready withdrawal of the extractor, or, rather, of the release of the extractor from the breech-block when the latter commences its backward movement. When, however, the pins v are so far down that the portions of larger diameter fit in the holes w, the extractors are locked fast in the breech-block and cannot be removed therefrom.

I also provide means whereby the pins v shall be raised when the gun is cocked, so that they will project above the barrel, as seen in Fig. 6, and indicate that the hammers are cocked. This means consists of two springs, s', arranged one under each pin v, having at their ends blocks or projections, upon which said pins rest. The natural tendency of the springs s' will throw them downward and permit the pins v to fall below the level of the top of the barrel; but the springs s' are arranged immediately above the mainsprings K', and consequently, when said mainsprings are moved up or deflected by the cocking of the hammers, they press upward the springs s', which, in turn, act upon the pins v and project them above the top of the barrel, indicating that the gun is cocked. When either of the hammers are down its mainspring K' will be down to its lowest position, and consequently the spring s' will spring down, permitting the pin v to fall below the level of the top of the barrel and out of sight, thus indicating that that hammer is not cocked. The sportsman, when sighting his gun, can see at a glance whether either of the hammers is cocked, and inasmuch as the hammers aid the sportsman in sighting, as the line of sight is between them, these pins accomplish the same purpose. The pins v are kept from falling out, in case of the gun being turned over, by means of two small pins, o', which engage with the portions v', which are of smaller diameter than the remaining portions of the pins v, and which are shown only in Fig. 9. It will be observed, with reference to said figure, that the firing-pins m are in close proximity to the indicator-pins v, and to enable them to pass by the said pins the firing-pins are recessed or notched upon one side, and they are therefore held in place in the breech-plugs I, and prevented from dropping out when the gun is cocked and stands upon its stock.

By my invention I produce a very strong and durable gun, which may be very conveniently handled, and in which the utmost pre-

caution is taken to prevent accidents resulting from its careless use.

What I claim as my invention, and desire to secure by Letters Patent, is—

1. The combination, in a breech-loading fire-arm, of a barrel and a base plate or piece, lugs upon one part engaging with recesses in the other part, a longitudinal rod for securing said barrel to said base plate or piece, and a breech-block, through which said rod passes, and which is movable upon said rod, substantially as specified.

2. The combination of the base-plate B, constructed with lugs b, the barrel A, constructed with recesses c, the round rod C, having a notch, d', in one side, and the spring d, engaging with said rod, substantially as specified.

3. The combination, in a breech-loading fire-arm, of a base plate or piece, a barrel mounted thereon, a longitudinal rod for securing said barrel to said base plate or piece, a movable breech-block fitting upon said base plate or piece, and through which said rod passes, and a locking-bolt movable transversely in said breech-block, and engaging with a notch in said rod, substantially as and for the purpose specified.

4. The combination, with a barrel, A, a base plate or piece, B, a longitudinal rod, C, and a breech-block, D, of a lever pivoted to said breech-block, and adapted to engage with a catch in said barrel, and a locking-bolt movable transversely in said breech-block and connected with said lever, and adapted to engage with a notch in said rod C, substantially as specified.

5. The combination of a movable breech-block, D, a barrel, A, a lever, G, pivoted to said breech-block, and adapted to engage with a catch upon the barrel, a lever, E, pivoted to said breech-block, and constructed with a shoulder, i, for acting upon the tail of said lever G, and a swinging link, F, all substantially as specified.

6. The combination of a base plate or piece, B, a barrel, A, a longitudinal rod, C, the end of which is notched, a movable breech-block, D, a lever, E, constructed with a notch, h, in one end, for engaging with said rod C, and a swinging link, F, all substantially as specified.

7. The combination, in a fire-arm, of a trigger, a leaf-spring for acting thereon, and a screw or pin, which forms a support for said spring, and which may be inserted in any one of a series of holes, whereby provision is afforded for adjusting the pull of the trigger, substantially as specified.

8. The combination, in a breech-loading fire-arm, of a breech-block constructed with a cylindric cavity, an extractor consisting of an annular portion adapted to fit in said cavity, and a projecting finger, provided at its end with an upturned lip, and a pin inserted transversely through said breech-block and extractor, substantially as specified.

9. The combination of a breech-block, *D*, constructed with a cylindric cavity, *j*, an extractor, *H*, comprising an annular or ring-shaped portion adapted to fit in said cavity, and constructed with holes *w* and narrower slots *w'*, and a pin, *v*, fitting in said holes and having portions of reduced diameter fitting said slots, substantially as and for the purpose specified.
10. The combination of a breech-block, *D*, a pin, *v*, inserted transversely through the breech-block, a hammer and trigger, a mainspring, and a spring, *s'*, arranged above said mainspring, and adapted to be raised by said main-
- spring to raise said pin, substantially as and for the purpose specified.
11. The combination, in a breech-loading fire-arm, of a movable breech-block, a lever, one end of which is pivoted to said breech-block, and a swinging link having a fixed fulcrum and a sliding connection with said fulcrum at one end, and pivoted to the said lever between the ends thereof, substantially as and for the purpose specified.
